US00D672455S

(12) **United States Design Patent**
Beck

(10) **Patent No.:** **US D672,455 S**
(45) **Date of Patent:** **** Dec. 11, 2012**

(54) **FLUID DELIVERY CASSETTE**

(75) Inventor: **Kent Beck**, Layton, UT (US)

(73) Assignee: **ZEVEX, Inc.**, Salt Lake City, UT (US)

(**) Term: **14 Years**

(21) Appl. No.: **29/376,123**

(22) Filed: **Oct. 1, 2010**

(51) **LOC (9) Cl.** **24-02**

(52) **U.S. Cl.** **D24/111**

(58) **Field of Classification** D24/108,
D24/111, 128-129; 128/DIG. 12; 417/477.1-477.2,
417/477.4-477.5; 604/67, 131, 151-154,
604/246, 249-250

See application file for complete search history.

CLAIM

The ornamental design for a fluid delivery cassette, as shown and described.

DESCRIPTION

FIG. 1 shows a left upper perspective view of a fluid delivery cassette made in accordance with the design of the present invention;

FIG. 2 shows a right upper perspective view of a fluid delivery cassette made in accordance with the design of the present invention;

FIG. 3 shows a bottom perspective view of a fluid delivery cassette made in accordance with the design of the present invention;

FIG. 4 shows a front view of a fluid delivery cassette made in accordance with the design of the present invention;

FIG. 5 shows a back view of a fluid delivery cassette made in accordance with the design of the present invention;

FIG. 6 shows a top view of a fluid delivery cassette made in accordance with the design of the present invention;

FIG. 7 shows a bottom view of a fluid delivery cassette made in accordance with the design of the present invention;

FIG. 8 shows a right side view of a fluid delivery cassette made in accordance with the design of the present invention; and,

FIG. 9 shows a left side view of a fluid delivery cassette made in accordance with the design of the present invention.

The broken lines shown in FIG. 5 represent portions of the fluid delivery cassette that form no part of the claimed design.
